UNITED STATES PATENT OFFICE.

JOSEPH W. GRIFFIN, OF NEW YORK, N. Y., AND FRANCIS M. McHUGH, OF WEEHAWKEN, NEW JERSEY.

TRAIN CONTROL.

1,253,027.

Specification of Letters Patent.

Patented Jan. 8, 1918.

Application filed October 4, 1915. Serial No. 53,966.

To all whom it may concern:

Be it known that we, JOSEPH W. GRIFFIN, a citizen of the United States, and a resident of the city of New York, borough of Manhattan, in the county and State of New York, and FRANCIS M. McHUGH, a citizen of the United States, and a resident of Weehawken, in the county of Hudson and State of New Jersey, have invented a new and Improved Train Control, of which the following is a full, clear, and exact description.

The invention relates to train controls, and an object thereof is to provide a simple, inexpensive and automatic contrivance controllable from the railway signals, and whereby a train will be positively prevented from passing a signal when the right of way is closed. A further object of the invention is to provide a train control whereby the train cannot be started until the signal indicates a free way to the train. A still further object of the invention is to provide a train control which is adapted to intercept the flow of energy to the prime mover of the train and also to release the pressure in the train line independently of the engineer's valves.

With the above and other objects in view, the nature of which will more fully appear as the description proceeds, the invention consists in the novel construction, combination and arrangement of parts as herein fully described, illustrated and claimed. In the accompanying drawings, forming part of the application, similar characters of reference indicate corresponding parts in all the views.

Figure 1 is a side elevation of the train control to be carried by the train;

Fig. 2 is a plan view thereof;

Fig. 3 is a side elevation of a steam locomotive provided with an embodiment of the invention;

Fig. 4 is an end view of the locomotive partly in section, with the railway signals for operating the train control carried by the locomotive;

Fig. 5 is a cross section through the valve mechanism for varying the pressure in the train pipe;

Fig. 6 is a perspective view of the cam shaft and the knuckles of the valve stems;

Fig. 7 is a cross section through the valve controlling the supply of steam to the cylinders of the locomotive;

Fig. 8 is a diagram of the wiring of the control mechanism; and

Fig. 9 is an axial section through the rotary switch controlling the rotation of the motor armature.

Before proceeding to a more detailed description of our invention it must be clearly understood that although the description and drawings relate to the application of the controlling mechanism to a steam locomotive, the same can be as efficiently applied to a locomotive operable by an internal-combustion engine or an electric motor. In the case of an internal-combustion locomotive the valve for cutting off the supply of fuel to the cylinders will be located in the manifold from the carburetor to the cylinders; and in the case of an electrically-operated locomotive, the means for cutting off the electricity to the motor will be located between the controller and the motor.

Referring to the drawings, 10 and 11 represent the semaphore signals, operable in the customary way, the corresponding rods of which are connected to switches 12 and 13 respectively. Located within the block controlled by the semaphore signals is a contact 14 and a rail 15 insulated from the contact 14 and extending parallel to the track for a length sufficient to retain the engagement of the rail with a contact shoe of the train after the stop of the train. The contact 14 is connected by a wire 16 to contact 16' of the switch 12. The cooperating contact 17' of the switch is connected by a wire 17 to a contact 17" of the switch 13. The rail 15 is connected by a wire 18 to another contact 18' of the switch 12, the other cooperating contact 19' of the said switch being connected by a wire 19 to a contact 19" of the switch 13. The contacts 20' and 20" form cooperating contacts with 17" and 19" respectively, the contacts 20' and 20" being grounded by a wire 20. It will be noted that when the signal 11 is operated the connection between the wires 18 and 19 and 16 and 17 is simultaneously disturbed or restored. When the signal 11 closes the right of way the switch 12 is closed. If the signal 10 also bars the right of way then the contact 14 is grounded,

as can be seen from the diagram. If the signal 11 bars the right of way, but the signal 10 shows a clear track, the rail 15 is grounded, as can be easily seen from the diagram.

5 The purpose of this will appear hereinafter.

The locomotive carries two contact shoes 21 and 22 for engaging the contact 14 and rail 15 when passing over the block controlled by the signals ahead. A wire 23 connects the shoe 21 to one pole of the solenoid 24, the other pole of the solenoid being connected by a wire 25 to a brush 26 of a rotary switch 27. One contact 28 of said switch is adapted to bridge the brush 26 with the brush 29 connected by a wire 30 to the source. A brush 31 of the switch 27 is connected to the wire 30. A contact strip 32 on the rotary part of the switch is adapted to bridge the brush 31 with a brush 33, 20 and which is connected by a wire 34 to one pole of a solenoid 35 similar to the solenoid 24, the other pole of the solenoid 35 being connected by a wire 36 to the shoe 22.

The cores 37 of the solenoids engage a beam 38 on the opposite sides of the pivotal axis of the beam, the connection being such that the beam is only operated by the downward movement of either of the solenoids. The end of the beam in proximity to the 30 solenoid 24 carries blades 39 for closing or opening a knife switch 40 located adjacent the solenoid 24. A similar switch 41 is located adjacent the solenoid 35, the blades 42 for opening or closing the switch 41 being carried by the end of the beam adjacent the solenoid 35. It will be noted that when the switch 40 is closed the switch 41 will be open, and vice versa.

The shaft 43 of the rotary switch is connected by a train of gears 44 to an electric motor 45. The switch 27 carries on one of its opposite faces metallic ring segments 47 and 47' and opposite ring segments 48 and 48' of a greater curvature disposed at right angles to the segments 47, 47'. The opposite faces of the switch are provided with spring-actuated brushes 49 and 49' and 50 and 50', the brushes 49 and 49' leading from the segments 47 and 47' respectively, and the brushes 50 and 50' leading from the segments 48 and 48' respectively. Interconnecting spring-actuated contacts 51 51' are provided on an insulating support 52 which faces the switch 27 so that the said contacts engage the segments 47. Interconnecting spring-actuated contacts 53 53' are also provided on said support 52 to engage with the segments 48 and 47' and 48. A brush 49 is mounted to travel on a metallic ring segment 54 provided on a support 55 of insulating material, and which faces the switch 27. The brush 50 is mounted to travel on a segment 56 of lesser curvature than segment 54 and also mounted on the support 55. The adjacent ends of the segments 54 and 56 are

staggered. The brushes 49' and 50' are mounted to travel respectively on segments 54' and 56', similarly related to each other as the segments 54 and 56.

It will be noted that the brushes 49 and 49' are diametrically opposite and are angularly disposed to the brushes 50 and 50', which are also diametrically opposite. The segments 54, 56 and 54' and 56' have substantially a length of arc of 90°. This causes 75 a circular gap between the adjacent ends of segments 54, 56' and 54', 56. During the rotation of the switch 27 to make a stop or clear the track, the contacts 51 51' and 53 53' remain always in engagement with their corresponding segments, but the brushes 49 and 49' will be off the segments 54, 54' when the switch 27 is in the position shown in the diagram on Fig. 8. In this position the switch is ready to make a stop. The brushes 80 50 and 50' will not be in engagement with the segments 56 and 56', so that current coming from the source 46 to the contacts 51 51' and 53 53' will pass through the segments 47 and 47' on the switch and into 90 the segments 54 and 54'. But when the switch is revolved through the length of the segments on the support 55, that is, through an angle of 90° in the direction indicated in the diagram, the brushes 50 and 50' will 95 enter into contact with the segments 56 and 56', and the brushes 49 and 49' will remain in contact with the segments 54 and 54'. At the end of travel of the switch 27 the brushes 49 and 49' will drop off the segments 54 100 and 54', while the brushes 50 and 50' will remain in contact with the segments 56 and 56' and, therefore, current will flow from the source through the segments 48 and 48' and into the segments 56 and 56', while the 105 current from the segments 54 and 54' would be cut off.

The segments 54 and 54' are connected by wires 57 and 57' to contacts 58 and 58' of the knife switch 40. The co-operating contacts 59 of contact 58 are connected by wires 60 to the armature and field of the motor 45. The co-operating contacts 59' of the contact 58' are connected by wires 60' to the armature and field, so as to complete the circuit 115 for the motor.

The segments 56 and 56' are connected by wires 61 and 61' to contacts 62 and 62' respectively. Co-operating contacts 63 of the contact 62 are connected by wires 64 to the field and armature of the motor 45. Co-operating contacts 63' of the contact 62' are connected by wires 64' to the armature and field to complete the circuit to the motor when the switch 41 is closed. It will be noted that the switches 40 and 41 cross the field wires 60 with 64' and wires 60' with 64. These switches, therefore, control the polarity of the motor and, consequently the direction of rotation, while the segments of 130

the support 55 control the length of time the motor is to be revolved in either direction.

As shown in Fig. 1, beam 38 is in normal 5 or ready-to-make a stop position. As a locomotive passes over with the signals barring the right of way, the solenoid 24 is energized and the beam 38 is drawn down, which brings the knives 39 into the blades 6, for the knuckles of said valve cannot be displaced when the cams A, B and C move in the direction indicated by the arrow. The operation of the valve 69 by the cam A is equivalent to the service application. 70 A further movement of the shaft 67 will bring the cam 68 into engagement with the valve 70. It will be noted that the cam D will displace the knuckle of the valve 72 without operating it. The operation of the 75 valve 70 is equivalent to the full service application of the brakes.

If the shaft 67 continues to rotate further, the cams D' and C come in contact with their respective valves 72' and 71, but 80 the valve 72' will remain unoperated, while the valve 71 will be raised, and this is equivalent to the emergency application of the brakes. To prevent the shaft 67 from opening the valve 64 before releasing the 85 brakes, the cam D' is so set that as soon as the shaft 67 is revolved in the opposite direction to what is shown in Fig. 6, the cam D' will operate the valve 72'. The valves 69, 70 and 71 will be closed and not depressed 90 during the reverse rotation of the shaft 67. This operation of the valve 72' will release the brakes before steam is admitted to the cylinder. The valve 72 serves to release the brakes in case the shaft 67 has not been rotated through a complete revolution. The reverse rotation of the shaft 67 will operate the valve 72 through the medium of the cam D and release the brakes before steam is fully admitted into the cylinders. 100

It should be clearly understood that the brushes 26 and 29 and 31 and 33 have no action on the working of the switch 27 other than to make and break the circuit after the rotary switch 27 revolves, thereby 105 making or breaking the solenoid circuits to avoid a drain on the battery.

Positioned between the throttle valve of the locomotive and the steam cylinders thereof is a valve 64 the stem of which carries a bevel gear 65 in mesh with a bevel pinion 66 carried by a shaft 67 geared to the shaft 43 of the motor. The shaft 67 is provided with cams 68 for operating valves 69 to 72 inclusive. The valves 72 and 72' establishes communication between the compressed air supply and the valve casing 74 which is connected to the train line only. Valves 69 and 71, located within the valve casing, control the communication thereof with the atmosphere, and whereby the pressure in the train line may be reduced. Normally all the valves are closed; but when the motor is caused to revolve by the closing of the switches 12 and 13 the shaft 43 will be revolved and therewith the shaft 67, the cams A, B and C being arranged to successively operate the valves 69, 70 and 71. They will only operate the valves when the shaft is rotated in 115 the direction of the arrow shown in Fig. 8, the contacts 19" and 20" will be bridged and the circuit to the solenoid 35 will be closed, for the contact 32 of the switch 27 will bridge the brushes 31 and 33. The closing of the switch 41 through the 120

To warn the engineer that the controlling device has been operated from the semaphore signals through contact 14, a red light 75 and a bell 76 in series are shunted with the solenoid 24. The solenoid 24 will be operated by the engagement of the shoe 21 with the contact 14, for the circuit to the solenoid will be completed through the switches 12 and 13, see Fig. 8. The operation of the solenoid will close the switch 40, 110 thus the circuit to the motor 45 will be closed and the operation of the motor will take place as previously stated. The displacement of the motor will break the connection between the brushes 29 and 26 and establish communication between the brushes 33 and 31. To cause the operation of the solenoid 24 the contact 14 should only be of sufficient length to produce a good contact with the shoe for operating the solenoid. To release the brakes and operate the valve of the train to admit the motive fluid to the cylinders, the relay or solenoid 35 is operated through the rail 15. By displacing the semaphore 10 to the dotted position shown in Fig. 8, the contacts 19" and 20" will be bridged and the circuit to the solenoid 35 will be closed, for the contact 32 of the switch 27 will bridge the brushes 31 and 33. The closing of the switch 41 through the 125

solenoid 35 will reverse the motor, which will operate the valves 72 and 72', which will raise the pressure in the train pipe and release the brakes. This rotation of the motor 5 will also open the valve 64. To warn the engineer that the solenoid 35 has been operated a buzzer 76' in series with a green light 75' is shunted with the solenoid. In place of operating the solenoid 35 from the signals 10 through the medium of the semaphore 10, the same can be made to be operated by the engineer, in which case a switch will be provided in the cab of the engine for controlling the circuit through the solenoid 35.

15 The contact 32 of the switch 27 is adapted to engage the brushes 31 and 33 as soon as the contact 28 breaks the connection between the brushes 26 and 29. The length of the contact 32 is such as to maintain this engagement between the brushes 31 and 33 through the entire displacement of the switch 27 by the motor 45 after the brushes 26 and 29 have been disconnected by the contact 28. Inversely the contact 28 is adapted to engage 25 the brushes only after the contact between the brushes 31 and 33 have been broken up by the contact 32. This bridging of the brushes 31 and 33 by the contact 32 during the displacement of the switch 27 by the 30 motor permits the operation of the solenoid 35 and, therefore, the reversal of the motor before it had completely displaced the switch 27.

When the motor has revolved, carrying 35 with it the rotary switch 27, and the operation of the air and steam has been completed, the train will be at stop. The rail 15 being in contact with the shoe 22, displacement of the signal 10 at the position shown in dotted 40 line in Fig. 9 causes the current to flow through the solenoid 35, the circuit for which has already been described. The beam 38 is drawn into the position shown in Fig. 1. The current will then flow from the 45 battery 46 to the brushes 51' and 53 through metallic ring segments 48' and 48 which are connected by brushes 50' and 50 to the segments 56' and 56. The segments are connected by wires 61' and 61 to the contacts 50 62' and 62 on opposite sides of the switch 41. Coöperating contacts 63' are connected by wire 64' to the field and armature of the motor 45, and coöperating contacts 63 are connected by wires 64 to the field and armature 55 of the motor 45. Since the field wires are crossed, the motor 45 will turn in the opposite direction and the rotary switch 27 will revolve through an angle of 90°; consequently, brushes 50 and 50' will drop off the 60 segments 56 and 56'. The steam valve will be opened and the train line will be charged through the valve 72 and 72'. The rotation of the switch 27 will bring the brushes 26 and 29 into contact with 28, while the 65 brushes 31 and 32 will drop off the contact

member 32. The system will then be ready for another operation, since the beam 38 will be in the position as shown in Fig. 1, that is, the solenoid 24 is ready to be energized through the medium of the switches 70 operable by the signals.

As shown in Figs. 1 and 2, the motor, switch, solenoids, valve casing, and the source of electricity are all mounted on a platform 76, so that the device is self-contained. When attached to a locomotive it is preferably placed to one side of the smoke box, as shown in Figs. 3 and 4. A box 77 fits over the platform to protect the device. It is self-evident that with different arrangements various transmission means can be provided from the shaft 67 to the means controlling the supply of motive power to the propelling means of the train. It will be noted that the circuit to the motor and solenoids will only be closed when the switches controlling the semaphore signals are operated.

While we have described the principle of operation, together with the device which we 90 now consider to be the best embodiment thereof, we desire to have it understood that the device shown is merely illustrative and that such changes may be made as are within the scope of the appended claims.

We claim:

1. In a train stop, a vehicle having propelling means, a signal, a contact, a shoe carried by the vehicle for engaging the contact, an open circuit, a switch controlled by the signal for closing the circuit through the shoe, a relay in the circuit, motive-power supply means for the propelling means of the vehicle, an electric motor, a circuit therefor, motion-transmission means from the 100 motor to the motive-power controlling means, a pole-changing switch operable by the relay, and a switch between the pole-changing switch and the motor operable by the movement of the motor for controlling 105 the rotation of the motor armature, said latter switch having means for controlling the current of the first circuit to the relay.

2. In a train stop, a vehicle having propelling means, a block signal, a contact and a contact rail disposed in the block controlled by the signal, shoes carried by the vehicle for engaging independently the contact and contact rail, open circuits, switches controlled by the signals for closing the 110 circuits through the contact or rail, a relay in the circuits, motive-power supply controlling means for the propelling means of the vehicle, an electric motor, a circuit therefor, motion-transmission means from the motor 115 to the motive-power supply controlling means, a pole-changing switch operable by the relay, and a switch between the pole-changing switch and the motor operable by the movement of the motor for control- 120

95

105

110

115

120

125

130

ling the rotation of the motor armature, said latter switch having means for controlling said open circuits to the relay.

3. In a train stop, a vehicle having propelling means, a block signal, a contact and a contact rail in the block controlled by the signal, shoes carried by the vehicle for engaging respectively the contact and contact rail, open circuits, switches controlled by the signal for closing the circuits through the contact or rail, a relay in the circuit through the contact and a relay in the circuit through the rail, motive-power supply controlling means for the propelling means of the vehicle, an electric motor, circuits therefor, motion-transmission means from the motor to the motive-power supply controlling means, a pole-changing switch operable by the relays, and a switch between the pole-changing switch and the motor and operable by the movement of the motor for controlling the rotation of the motor armature, said latter switch having means for controlling the current of the circuits through the relays.

4. In a train stop, a vehicle having propelling means, a block signal, a contact and contact rail in the block controlled by the signal, shoes carried by the vehicle for engaging respectively the contact and the rail, open circuits, switches controlled by the signal for closing the circuits through the contact or rail, a relay in the circuit of the contact and a relay in the circuit of the rail, motive-power supply controlling means for the propelling means of the vehicle, an electric motor, a circuit therefor, motion-transmission means from the motor to the motive-power controlling means, a pole-changing switch operable by the relays, and a rotary switch between the pole-changing switch and the motor operable by the movement of the motor for controlling the rotation of the motor armature, said rotary switch having means for controlling the current of the first circuits to the relays so that the motor can be reversed before it reaches the end of its travel.

5. In a train stop a vehicle having propelling means, a block signal, a contact and contact rail in the block controlled by the signal, shoes carried by the vehicle for engaging respectively the contact and rail, open circuit in which the shoes are contained, switches controlled by the signal for closing the circuits through the contact or rail, a relay in the circuit through the contact and a relay in the circuit through the rail, motive-power supply controlling means for the propelling means of the vehicle, an electric motor, circuits therefor, motion-transmission means from the motor to the motive-power controlling means, a pole-changing switch operable by the relays, a rotary switch between the pole-changing

switch and the motor operable by the movement of the motor for controlling the rotation of the motor armature, and means operable by the rotary switch for closing the first circuit to one of the relays and breaking the 70 circuit to the other, and vice versa.

6. In a train stop, a vehicle having propelling means, a block signal, a contact and a contact rail in the block controlled by the signal, shoes carried by the vehicle for engaging respectively the contact and contact rails, open circuits, switches controlled by the signal for closing the circuits through the contact or rail, a relay in the circuit through the contact and a relay in the circuit through the rail, a second switch in the circuits adapted to close the circuit to one of the relays while maintaining the circuit open to the other, and vice versa, motive-power supply controlling means for the propelling means of the vehicle, a brake system for the vehicle, means for operating the same, an electric motor, a circuit therefor, motion transmission means from the motor to the motive-power supply controlling 80 means and the means for operating the brake system, a pole-changing switch for the motor operable by the relays, said second switch being operable by the motion-transmission means, and means between the pole-changing switch and the motor operable by the movement of the second switch for controlling the rotation of the motor armature.

7. In a train stop, a vehicle having propelling means and a brake system, a block signal, a contact and a contact rail in the block controlled by the signal, shoes carried by the vehicle for engaging respectively the contact and contact rail, an open circuit containing one of the shoes and a similar circuit containing the other shoe, a relay in each of the circuits, a rotary switch for breaking one of the circuits while closing the other, and vice versa, switches controlled by the signal for closing the circuit through the contact or rail, motive-power supply controlling means for the propelling means of the vehicle, means for operating the brakes, an electric motor, a circuit therefor, motion-transmission means from the motor to the power-supply controlling means and means for operating the brake, a pole-changing switch for the motor operable by the relays, said rotary switch being operated by the motion-transmission means, and means operable by the rotary switch for controlling the rotation of the motor armature.

8. In a train stop, a vehicle having propelling means and a brake system, a block signal, a contact and a contact rail in the block controlled by the signal, shoes carried by the vehicle for engaging respectively the contact and contact rail, an open circuit including one of the shoes and a similar circuit including the other shoe, a relay in 125

- each circuit, switches controlled by the signal for completing the circuit through the contact or rail, motive-power supply controlling means for the propelling means of 5 the vehicle, means for operating the brakes, an electric motor, a circuit therefor, motion-transmission means from the motor to the motive-power supply controlling means and the brake operating means, a pole-changing 10 switch for the motor operable by the relays, a rotary switch operable by the motion-transmission means adapted to complete either of the open circuits while the other is maintained open, and a switch between 15 the pole-changing switch and the motor operable by the rotary switch for controlling the rotation of the motor armature.
9. In a train stop, a vehicle having a brake system including a train line, a valve casing 20 connected to the train line, valves in said valve casing, a cam shaft for operating said valves successively whereby the train line is controlled, an electric motor for revolving said cam shaft, a circuit for said motor, a 25 pole-changing switch in the circuit or reversing motor, a rotary switch operable by the motor in the circuit between the pole-changing switch and the electric motor for controlling the rotation of the motor armature, a block signal for the vehicle, a contact and contact rail in the block controlled 30 by the signal, shoes carried by the vehicle for engaging respectively the contact and the contact rail, an open circuit to one of the 35 shoes, a similar circuit to the other shoe, a relay in each of the open circuits, said pole-changing switch being operable by the relays, a switch controlled by the rotary switch for completing either of the open circuits 40 while the other is maintained open, and a switch controlled by the signal for closing the circuit through the contact or rail.
10. In a train stop, a vehicle having an air-brake system including a train line, a 45 valve casing connected to the train line, valves in said casing, a cam shaft, said valves having means engageable by the cams and so related that some of the valves are operated when the shaft is rotated in one 50 direction and the other valve is operated when the shaft is rotated in the opposite direction, a motor for revolving said shaft, a circuit for said motor, a pole-changing switch in the circuit for reversing the motor, a switch operable by the motor and in 55 the circuit between the pole-changing switch and the motor for controlling the rotation of the motor armature, a signal for the vehicle, a contact and contact rail in the block controlled 60 by the signal, shoes carried by the vehicle for engaging respectively the contact and contact rail, an open circuit including independently each of the shoes, a solenoid for each of the open circuits, said pole-changing switch being operable by the sole- 65

noid, a switch controlled by the rotary switch for connecting one of the solenoids to the corresponding open circuit while disconnecting the other from its corresponding circuit, and a switch controlled by the signal 70 for closing the circuit through the contact or rail whereby the corresponding open circuits are completed.

11. A train-stop mechanism comprising,— a valve casing, valves in the casing, a cam 75 shaft for operating said valves, means associated with said valves for causing the operation thereof when said shaft revolves in a predetermined direction, an electric motor for revolving said shaft, a circuit therefor, a pole-changing switch in the circuit for reversing the motor, a rotary switch operable by the motor in the circuit between the pole-changing switch and the electric 80 motor for controlling the rotation of the motor armature, a solenoid for operating the pole-changing switch, an open circuit therefor, and a switch controlled by the rotary switch for bringing the solenoid into the open circuit.

12. In a train stop, the combination of a vehicle having an air-brake system including a train line, a valve casing connected to the train line, valves in the casing, a cam shaft for operating said valves, means associated with the valves causing the same to be operated when the shaft is rotated in a predetermined direction, whereby the air pressure in the train line may be lowered or raised, an electric motor for revolving 90 said shaft, electrically-operated means associated with the motor for controlling the rotation and the direction of rotation of the motor, a block signal for the vehicle, an open circuit for the electrically-actuated 95 means, and a switch for completing the open circuit operable by the block signal.

13. A train-stop mechanism comprising,— an electric motor, an insulated member revoluble by said motor, pairs of diametrically opposite arcuated metallic segments carried by said insulated member so that the same are disposed angularly to each other, stationary pairs of contacts for engaging the pairs of segments, current-supplying means associated with the pairs of contacts, a brush from each of the segments, stationary pairs of diametrically opposite arcuated metallic segments disposed angularly to each other for engaging the brushes, the angular relation between said last-mentioned pairs of segments being such that the displacement of the revoluble insulated member by the motor causes one pair of brushes to disengage the co-operating pair of segments, while the other pair of brushes engages the other pair of co-operating segments, electric conduits from the pairs of segments to the field and armature of the motor, a pole-changing switch for 110 115 120 125 130

- connecting one pair of the stationary segments to the field and armature while disconnecting the other pair, a pair of solenoids for operating the pole-changing switch, an open circuit to each of the solenoids, a switch in each of the open circuits, and means carried by said insulated revoluble member for closing one of the switches while opening the other.
- 10 14. In a train stop, a signal, a contact, a shoe for engaging the contact carried by the train, an open circuit, a switch for closing the circuit controlled by the signal, a relay, a switch controlling the circuit to the relay, electro-motive means for cutting off the motive power of the train and operating said relay switch, and means controlling the electro-motive means operable by the relay.
- 15 15. In a train stop, an electric motor, electrically operable means for reversing the direction of rotation of the motor, a block sig-

nal, open circuits for the electrically operable means, and switches for closing the circuit operable by the block signal.

16. In a train stop, a brake system including a train line, a valve casing connected to the train line, valves in said valve casing, a cam shaft for operating said valve successively, an electric member for revolving said cam shaft, electrically-operable means for reversing the direction of rotation of the member, a block signal, open circuits for the electrically-operable means, and switches for closing the circuits operable by the block signals.

In testimony whereof we have signed our names to this specification in the presence of two subscribing witnesses.

JOSEPH W. GRIFFIN.
FRANCIS M. McHUGH.
